UNITED STATES PATENT OFFICE.

KOSTA R. MILOVANOVITCH-KOKA, OF VIENNA, AUSTRIA-HUNGARY.

MAGAZINE FIRE-ARM.

SPECIFICATION forming part of Letters Patent No. 413,078, dated October 15, 1889.

Application filed December 4, 1888. Serial No. 292,685. (No model.) Patented in Germany October 30, 1888, No. 47,777; in France October 30, 1888, No. 193,806; in Belgium October 30, 1888, No. 83,779; in Switzerland November 15, 1888, No. 46, and in Italy December 31, 1888, Nos. 128 and 24,320.

To all whom it may concern:

Be it known that I, KOSTA R. MILOVANOVITCH-KOKA, lieutenant-colonel and military attaché of the King of Servia, a subject of the King of Servia, residing at Vienna, in the province of Lower Austria, in the Empire of Austria-Hungary, have invented certain new and useful Improvements in Magazine Fire-Arms, (for which I have obtained Letters Patent in Germany, dated October 30, 1888, No. 47,777; in France, dated October 30, 1888, No. 193,806; in Belgium, dated October 30, 1888, No. 83,779; in Italy, dated December 31, 1888, Nos. 128 and 24,320, and in Switzerland, dated November 15, 1888, No. 46;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Referring to the drawings, Figure 1 is an isometric view of so much of a bolt-gun as is necessary to illustrate the application of my improved magazine to this style of guns. Fig. 2 is a like view, the magazine being removed to more clearly illustrate the feed-slot 25 in the side of the receiver. Fig. 3 is a side elevation of the receiver of a bolt-gun provided with a lateral feed slot or aperture. Figs. 4 and 5 are sections taken on lines $x-x'$ and $x'-x'$, respectively, of Fig. 3, and as seen when looking in the direction of the arrows 30 and 2. Fig. 6 is a side elevation of the magazine, the lower portion thereof being broken away. Figs. 7, 8, 9, and 10 are transverse sections of the receiver and magazine applied thereto, illustrating, respectively, the mode 35 of feeding the cartridges to the receiver and the mode of supplying the magazine. Fig. 11 is an isometric view of a package of cartridges put up for use with my improved magazine. Fig. 12 is a like view of the receptacle or holder for the cartridges shown in Fig. 11. Fig. 13 is a top plan view of the receiver of the gun and the magazine applied thereto; and Fig. 14 is a top plan view of the magazine,

showing the partially-withdrawn cartridge-case in transverse section.

The object of this invention is to improve the efficiency of breech-loading guns by providing means whereby the marksman is enabled at any time to ascertain the number of cartridges in the magazine, supply the same with cartridges singly or in packs or packages at any time, whether the magazine is partly or wholly exhausted, and whereby the feeding of the cartridges to the receiver or the breech-chamber is rendered independent of the action of the bolt or breech mechanism.

To these ends the invention consists in the peculiar construction of the magazine and its combination with a breech-loader having a feed-slot formed in the receiver, substantially as hereinafter fully described, and as set forth in the claims.

The invention further consists in the combination, with the magazine, of a cartridge-case of peculiar construction for supplying the magazine with cartridges, and in other minor structural features and combinations of parts, substantially as hereinafter fully described, and as specifically pointed out in the claims.

The improved magazine is so constructed as to always present a cartridge in such a position that it may be pushed by hand directly into the breech-chamber of the gun when the breech is open whether the gun is provided with a pivoted breech-block, as in the Peabody or Martini rifle, or with a revoluble block, as in the Werndl rifle, or with a sliding bolt, so that the feeding of the cartridge to the breech-chamber is in a measure independent of the action of the breech mechanism should such mechanism fail to carry the cartridge forward into the chamber; but that my invention may be fully understood I will describe the same, reference being had to the accompanying drawings, wherein—

B indicates the receiver of a bolt-gun that has formed in one of its lateral walls an opening B' of varying diameter to afford a passage to the cartridges from the magazine to said receiver.

As shown in Figs. 2, 3, 4, and 5, the opening or slot B' for about two-thirds of its length from front to rear, or from a point p to a point p', is of such a diameter as to afford a free passage to the corresponding part of a cartridge, while the rear end of said slot B' is of such a diameter as to allow but a small portion of a cartridge and its flange to project into the receiver. The upper and lower walls 10 b are so constructed as to vanish or taper toward the breech-chamber and inwardly toward the receiver, thus forming inclined planes or surfaces relatively to the longitudinal axis of the receiver, so that a cartridge 15 lying within the slot will lie at an angle to said axis, as more plainly shown in Fig. 13. At their terminal or forward end the inwardly-inclined walls b merge into shallow grooves b', that are segmental in cross-section 20 and are of gradually-increased width from their rear to their front ends to afford passage to and guide the rear portion and flange of the cartridge from the slot into the receiver when pushed forward either by hand 25 or by the breech-bolt, so that each cartridge is guided by the slot until the projectile end of said cartridge has fully passed into the breech or chamber of the barrel, as shown in dotted lines in Fig. 13, when the said cartridge 30 will be free to move out of the opening B', it being then guided by the breech-chamber.

Although I prefer to form a slot or opening of the construction described in one side 35 of the receiver, yet this is not absolutely necessary, as such a discharge-mouth may be connected with or formed on the magazine, the outer faces of such mouth being rectangular and fitting into a corresponding slot in 40 the receiver-wall.

The magazine consists, essentially, in an open-top casing A, of substantially polygonal form, in whose front and rear walls is formed a slot a⁵, near the lower end of which is a notch 45 a¹⁵, Fig. 1. The cartridges are fed to the upper open end of the magazine by a spring a, having the usual follower secured to its free end, said follower being provided with lugs a³, that project through the end-wall slots a⁵ 50 of the magazine. By compressing the spring a and moving the lugs or ears a³ into the notches a¹⁵ said spring may be held in a compressed state, for purposes presently to be explained.

To prevent the cartridges from being ejected 55 through the upper open end of the magazine and to guide said cartridges laterally under the stress of their feed-spring, I provide a spring-cover A', composed of an elastic or 60 spring plate or shank a', whose upper end is bent at an angle to the vertical and projects over the mouth or upper end of the magazine and constitutes the cover. The cover portion is so constructed as to form two diverging 65 arms a³¹, the outer edges of which are bent at right angles, or nearly so, as shown in Figs. 1, 6 to 10, and in Fig. 13, to form project-

ing lugs or ears a⁶, there being an opening a²¹ between said diverging arms a³¹. The elastic shank a' of the cover A' has its lower 70 end A² re-enforced, and is secured to the front wall of the magazine by means of a screw a¹¹, that passes through such re-enforced portion and through a slot in said front wall, said screw also serving to secure to the re-enforced portion A² of the cover-shank a' a spring-catch a⁹, that projects through a slot 75 in a thumb-piece A³, formed on the foot of the shank a'.

By means of the described arrangement the 80 cover A' may be moved down and locked to the magazine to prevent the cartridges from passing out of the magazine laterally, as shown in Fig. 8, when it is desired to load the gun in the usual manner.

As shown in Fig. 7, the inclined diverging arms a³¹ of the cover or lid A' form a guide to guide the cartridges laterally into the slot B' of the receiver or into the discharge-opening of the magazine. To insure that such 90 cartridges will move into said slot at the desired angle relatively to the longitudinal axis of the receiver and breech-chamber, I provide a lug that is secured to the free end of a flat spring a⁸, Figs. 1, 6, and 13, secured to the 95 front wall of the magazine. The lug projects through an opening in said front wall and impinges upon the forward end of the cartridges as they are brought in position, thus forcing or guiding said forward end of the 100 cartridges laterally, so that each cartridge as it reaches a position to enter the feed-opening in the receiver will lie at the proper inclination thereto.

Inasmuch as the end walls of the magazine 105 are slotted, the marksman can see at all times the number of cartridges therein. To avoid any mistake, both end walls or the rear end wall of the magazine may be graduated and such graduations properly spaced according 110 to the number of cartridges the magazine will hold, and numbered from top downward, as shown in Fig. 1, the projecting lug or ear a³ on the follower serving as an index to indicate the number of cartridges in or remaining in the magazine.

By providing a spring cover or lid A', as described, the magazine may be supplied with cartridges at any time, either singly, when the magazine is not exhausted, or collectively 120 by introducing a package of such cartridges by moving the spring-cover A' outwardly, the ears a⁶ serving as hand-holds or as guides. By these means, when an order of "cease firing" is given and the cartridges in the magazine are not exhausted, the marksman may, without removing the magazine from the gun, replenish it with cartridges from his pouch, by introducing them singly, the feed-spring being first compressed and locked against expansion to allow the remaining cartridges to 125 drop down. The projectile end of a cartridge is then introduced into the opening a²¹ of the spring-cover A', causing it to bear 130

against the under side of the front arm a^3 of said cover, the rear end of the cartridge being pressed against the inner face of the rear vertical lug a^6 , thereby forcing the cover outward and permitting the cartridge to drop into the magazine. In this manner cartridge after cartridge may be introduced until the magazine is filled again.

To load the magazine at a single operation, 10 the required number of cartridges are put up into a package, the holder for the cartridges being of proper construction. This holder C, Figs. 9 to 12, consists of a sheet-metal case open at top, bottom, and on one side, the converging flanges at the open front side, as well as a portion of the rear wall, being slotted from the lower edge upwardly to form spring retaining-tongues c^3 , the lower end of which is bent inwardly to hold the tier of cartridges, 15 a central ear c being formed at the upper edge of the back wall that projects across the open top of the case, and to said ear is secured a loop c^4 of leather or other suitable material. At one end of the open top of the 20 case C the metal is bent over to form an inwardly-projecting flange c^5 , that serves to retain the projectile or smaller end of the cartridges.

As constructed a single cartridge may be 25 readily withdrawn from the case when it is desired to replenish a partly-empty magazine in the manner above described. This case C is of such size as to fit inside of the magazine, and can be readily introduced after locking the feed-spring against expansion and moving back the spring-cover A', which may be effected by pressing the rear end of the case C against the rear vertical lug or ear a^6 of the magazine, the case being held so that its 30 rear wall c^6 will be parallel with the corresponding wall of the magazine A, thereby moving the spring-cover a' out of the way, when said case C may be pushed into the magazine. As soon as the case C is fully 35 pushed in, the cover springs back into position, its diverging arms lying on opposite sides of the ear c of the cartridge-case, and the latter may then be pulled out by the strap c^4 , the diverging arms a^3 of the cover preventing the cartridges from moving with the case, while the strain exerted will cause the 40 retaining-tongues c^3 to spread, thus leaving the cartridges in the magazine. In this manner of loading it is not absolutely necessary 45 to lock the feed-spring a against expansion, as the case of cartridges may be pushed into the magazine against the stress of said spring, as will be readily understood. Of course the 50 spread of the diverging arms of the bent portion A' of the spring-cover a' is such as not to overlap the opposite ends of the cartridge-case C when inserted in the magazine, so as to permit of its withdrawal, as described.

To properly guide the cartridge-case when 55 it is inserted into the magazine, the opposite ends of the latter are extended vertically to form guide-lugs or ears a^7 , as shown. As

soon as the cartridge-case C is fully withdrawn from the magazine, the spring-follower, in conjunction with the inclined cover A' and the spring-lug a^8 , impels the upper cartridge into the discharge-mouth of the magazine or the slot B' in the receiver, as shown in Fig. 7.

If it is desired to use the gun in the ordinary manner, by inserting the cartridges singly 60 into the receiver after each shot, through the top opening, the cartridges in the case are locked against vertical and lateral motion by pulling down the spring-cover, so that the catch a^9 will engage the bottom of the magazine, as shown in Fig. 8, the spring-shank of the cover being properly guided in this movement by guide-flanges a^2 , secured to the front wall of the magazine, as shown in Fig. 1. When the spring-catch is released, the cover 65 will be automatically returned into its normal position by the pressure exerted by the feed-spring a . Inasmuch as the power of the feed-spring is not exerted uniformly upon the whole cover by reason of the varying diameter of the cartridges, there is a tendency to lateral movement of said cover, to avoid which I employ the locking-lever a^{10} , Figs. 1 and 6.

In view of the described construction of the 70 slot B' or the discharge-mouth of the magazine a cartridge dropped into the receiver from above cannot penetrate into the lateral slot, so that all danger of a cartridge becoming wedged in the receiver or all danger of 75 an empty shell becoming so wedged in the receiver is avoided.

The magazine may be permanently secured to the gun, as shown in Fig. 1, or it may be 80 detachably secured thereto, as shown in Figs. 85 2 to 6, to which latter end the magazine has a stud a^{12} projecting from the inner edge of its end wall, said studs fitting into socket-pieces a^{13} , in the rear one of which is arranged 90 a locking-bolt a^{14} , preferably actuated by a coiled spring on the bolt within the socket and tending to draw the bolt inwardly.

It will be seen that by the means described the difficulties first above referred to are effectually overcome, the improvements being 95 simple in construction and comparatively inexpensive, and are applicable to any of the existing breech-loading guns, and may be applied to either side of the gun. In guns of the Mauser, Gras, Le Bel, Berdan, Martini, and Werndl 100 systems the magazine may be applied with greater advantage to the left side of the receiver, while it may be secured to either side of guns of the Mannlicher and Wetterli systems.

Although I have described a simple and 105 cheap manner of putting up the cartridges in packages, yet this is not essentially necessary, as has been explained, and as is the case with the Mannlicher magazine, in which special 110 cartridge-packages are necessary. Finally, I would state that it is not absolutely necessary 115 that the cartridges be lifted to the discharge end of the magazine, but that the position of

the latter may be reversed and the cartridges fed to the gun by gravity; or the magazine may be arranged in a more or less horizontal plane relatively to the gun.

5 Having described my invention, what I claim is—

1. In a breech-loading gun, a receiver provided with a longitudinal slot in one of its sides and a guide composed of guide-ribs extending partly along the slot toward the receiver and at an angle to its longitudinal axis to guide the cartridge-bullet end foremost into the receiver and breech-chamber at a point in proximity to the latter, in combination with a magazine provided with suitable means to force the cartridge into said slot, substantially as and for the purposes specified.

2. In a breech-loading gun, the combination, with the receiver provided with a longitudinal slot in one side thereof, the forward portion of said slot being wider than the rear portion, said narrower rear portion being formed by guide-ribs arranged at an angle to the longitudinal axis of the receiver, of a magazine and a guide to guide the cartridges therefrom into the slot, substantially as and for the purposes specified.

3. In a breech-loading gun, the combination, with the receiver provided with a longitudinal slot in one of its sides, the forward portion of said slot being wider than the rear portion, said narrower rear portion being formed by guide-ribs arranged at an angle to the longitudinal axis of the receiver, and said ribs merging into guide-grooves, of a magazine and a guide to guide the cartridges therefrom into the slot, substantially as and for the purposes specified.

4. In a breech-loading gun, the combination, with the receiver provided with a longitudinal slot in one of its sides, the forward portion of said slot being wider than the rear portion, said narrower rear portion being formed by guide-ribs arranged at an angle to the longitudinal axis of the receiver, of a magazine and an elastic guide to guide the cartridges therefrom into the slot, said guide being provided with an opening leading into the magazine for the purpose of feeding the cartridges to the breech-chamber by hand, substantially as and for the purposes specified.

5. In a breech-loading gun, the combination, with the receiver provided with a longitudinal slot in one of its sides, of a magazine and a vertically-adjustable guide-cover therefor, consisting of an elastic plate having diverging arms extending over the open end of the magazine and arranged at an angle to the longitudinal axis of the receiver, substantially as and for the purposes specified.

6. In a breech-loading gun, the combination, with the receiver provided in one of its sides with a longitudinal slot whose rear portion is narrower than its front portion, said narrower portion being formed by guide-ribs

arranged at an angle to the longitudinal axis of the receiver and merging into guide-grooves, of a magazine provided with a vertically-adjustable elastic cover arranged at an angle to the horizontal and a spring lug or finger projecting into the magazine and adapted to impinge on the projectile end of the cartridges, substantially as and for the purposes specified.

7. In a breech-loading gun, the combination, with the receiver, of a magazine having its rear wall slotted vertically and provided with a graduated index, a feed-spring and follower, and a pointer connected with said follower and arranged to travel along the graduated index, substantially as and for the purposes specified.

8. In a breech-loading gun, the combination, with the receiver and a magazine and a laterally-movable cover shorter than said magazine and having a central opening or cut-away portion to form two diverging arms, of a cartridge-case open at top, bottom, and one side, and provided with spring-fingers at its lower edge to retain the cartridges therein, and with an ear projecting centrally across the open top, said case fitting into the magazine, substantially as and for the purposes specified.

9. In a breech-loading gun, the combination, with the receiver provided with a longitudinal slot in one of its sides, the forward portion of said slot being wider than the rear portion thereof, said narrower rear portion being formed by guide-ribs *b*, arranged at an angle to the longitudinal axis of the receiver and merging into grooves *b'*, of a magazine provided with a vertically and laterally movable cover arranged at an angle to the horizontal, a spring-actuated follower, and the locking-lever *a*¹⁰, substantially as and for the purposes specified.

10. A magazine for breech-loading guns, consisting of a rectangular receptacle or case and a spring-cover composed of the spring-shank *a'* and the inclined diverging arms *a*³¹, provided with the lugs or ears *a*⁶, said cover being secured to the box by a screw extending through a vertical slot in said box, in combination with a locking-lever *a*¹⁰, for locking the cover against lateral movement, substantially as and for the purposes specified.

11. A magazine for breech-loading guns, consisting of a rectangular receptacle or case having vertical slots formed in both end walls and provided with an index graduated to the number of cartridges the magazine can hold, the graduations being numbered from top downward, and a horizontal slot *a*¹⁵ near the lower end of and merging into said vertical slots, and a spring-actuated follower arranged within the magazine and having extensions or lugs *a*³ projecting through the vertical end slots of the magazine, substantially as and for the purposes specified.

12. A magazine for breech-loading guns, consisting of a rectangular receptacle and

a cover therefor, composed of the diverging inclined arms a^3 , provided with lugs or ears a^6 , the re-enforced portion A^2 , terminating in a slotted thumb-plate A^3 , and an intermediate spring-shank a' , said cover being secured to the front wall of the receptacle by a screw a^{11} , passing through the re-enforced portion of the cover-shank and through a slot in said receptacle, in combination with a spring-
10 catch a^9 , secured by said screw a^{11} to the cover-shank and extending through the slot of the thumb-plate, substantially as and for the purposes specified.

13. A magazine for breech-loading guns, consisting of a rectangular receptacle and a cover therefor, composed of diverging and laterally-movable spring-arms terminating in a

hand-hold, the spread of said arms being less than the length of the box and constructed to form a notch or recess between them, in combination with a cartridge-case C, open at top, bottom, and front, and provided at its lower edge with spring-fingers c^8 , with the outwardly-bent flange c^5 along the upper edge at one end, and with the central lug or ear c , provided with a strap c^4 , said case being adapted for insertion into the magazine, substantially as and for the purposes specified.

In testimony whereof I affix my signature in presence of two witnesses.

KOSTA R. MILOVANOVITCH-KOKA.
